United States Patent

Des. 236,791
Patented Sept. 16, 1975

236,791

BAKING STONE

Pasquale N. Bruno, Elmhurst, and James L. Stewart, Lake Zurich, Ill., assignors to Old Stone Oven Corporation, Elmhurst, Ill.

Filed Oct. 23, 1973, Ser. No. 408,648

Term of patent 14 years

Int. Cl. D7—02

U.S. Cl. D7—123

Fig. 3.

FIG. 1 is a top front perspective view of the baking stone showing our new design;

FIG. 2 is a bottom plan view thereof taken in the direction of the arrows 2—2 in FIG. 1; and

FIG. 3 is a cross-sectional view taken on line 3—3 of FIG. 2.

We claim:

The ornamental design for a baking stone, as shown and described.

References Cited

UNITED STATES PATENTS

D. 138,062	6/1944	Breen	-----	D7—130
D. 225,323	12/1972	Smith	-----	D18—2 B
2,355,568	8/1944	Smith	-----	D18—2 B

WALLACE R. BURKE, Primary Examiner

C. KEMPER, Assistant Examiner